Primary Examiner — Paula Greene*(74) Attorney, Agent, or Firm* — Banner & Witcoff, Ltd.(57) **CLAIM**

The ornamental design for earcups for a headset, as shown and described.

DESCRIPTION

FIG. 1 is a front perspective view of earcups for a headset showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a perspective view of the design showing one earcup in isolation for clarity purposes; and,

FIG. 9 is a right view thereof.

The broken line showing of the remainder of the headset is for environmental purposes only and forms no part of the claimed design.

1 Claim, 9 Drawing Sheets(56)
